US0D1095478S

(12) **United States Design Patent** (10) Patent No.: **US D1,095,478 S**
(45) Date of Patent: ** Sep. 30, 2025

(54) **WIRELESS COMMUNICATION
TRANSCEIVER**

(71) Applicant: **Ryder Electronics (Xinfeng)Ltd.**,
GanZhou (CN)

(72) Inventors: **Kip Yuan**, Zhuhai (CN); **Zime Wen**,
Zhuhai (CN); **Loomis Liu**, Zhuzhou
(CN); **Aikin Zhu**, Zhuzhou (CN)

(73) Assignee: **Ryder Electronics (Xinfeng) Ltd.**,
GanZhou (CN)

(**) Term: **15 Years**

(21) Appl. No.: **29/926,569**

(22) Filed: **Jan. 31, 2024**

(30) **Foreign Application Priority Data**

Sep. 28, 2023 (CN) 202330641157.2

(51) **LOC (15) Cl.** **14-01**

(52) **U.S. Cl.**

USPC **D14/137**

(58) **Field of Classification Search**

USPC D14/137, 144, 155, 188, 206, 224, 225,

D14/226, 227, 228, 229, 230

(57) **CLAIM**

The ornamental design for a wireless communication transceiver, as shown and described.

DESCRIPTION

FIG. 1 is a front, right and top perspective view of a wireless communication transceiver, showing our new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the wireless communication transceiver that form no part of the claimed design.

1 Claim, 8 Drawing Sheets
